TAG FOR FLOOR COVERINGS OR THE LIKE

Sidney Rosenthal, Great Neck, N. Y., assignor to
Pilgrim Badge and Label Corporation, Cam-
bridge, Mass., a corporation of Massachusetts

Application March 24, 1938, Serial No. 197,847

2 Claims. (Cl. 40—2)

This invention relates to tags more particularly of the kind to be attached to floor coverings, such as rugs and carpets, or to like articles of commerce that are displayed for sale with a tag that serves to identify the manufacturer as well as to give the salesman and the customer such information as price, dimensions, etc. Such tags, which are commonly made of textile fabric or cloth so as not to be torn in being grasped or handled repeatedly in association with a comparatively heavy rug or similar article, frequently comprise a portion adhesively united or bonded firmly to the back of the rug and a flap or portion projecting beyond the margin of the rug. The portion united to the rug usually carries the name of the manufacturer and/or his trademark and is intended to remain permanently united to the back of the rug after the rug is sold. The flap portion presents to ready view, even when the rug or like article forms part of a pile, such desired information as the manufacturer and/or his trademark, preferably on one face, and such desired information as the price, dimensions, etc., preferably on the opposite face. The tag of the present invention is of the foregoing type and is characterized by the ease and economy with which it may be manufactured and by the satisfactory results had therefrom in service. It comprises two pieces or sections, namely, a fabric or cloth section, which is adapted to be adhesively united to the back face of the floor covering, and a double-texture fabric or cloth section, which is marginally bonded to the first-named section and is adapted to constitute the flap portion of the tag. The first-named tag section, which may for convenience of designation be termed the fixable tag section by reason of its permanent fixation to the back of the floor covering, is print-receptive on its outer face and carries the desired indicia imprinted thereon, whereas the inner face of such section is coated with normally non-adhesive but adhesively activatable substance for the purpose of enabling the desired adhesive union of such section with the back of the floor covering. The second-named tag section or flap portion comprises a marginal portion that laps and is adhesively united to the marginal portion of the adhesive-coated face of the fixable tag section. Because the flap portion is a double-texture fabric, it may be readily and economically made to be print-receptive on both its faces and thus to carry the desired indicia imprinted thereon. Moreover, the flap portion or section, although a double-texture fabric, may readily and advan-

tageously be made more flexible than the fixable tag section, which should be coated sufficiently thickly with the adhesively activatable substance to ensure the desired tenacious fixation thereof to the back of the floor covering. In this latter connection, it might be observed that the necessary comparatively thick coating of the usual adhesively activatable substances on the inner face of the fixable section stiffens it considerably. Nevertheless, because the flap portion or section is comparatively flexible, it bends or flexes readily, as desired, at a region thereof immediately beyond the boundary of the adhesive joint formed between the two tag sections and may thus droop freely or be bent readily upwardly when it is to be inspected for the particular information concerning the rug with which it is associated and which may form part of a pile.

With the foregoing and other features and objects in view, the invention hereof will now be described in further detail with particular reference to the accompanying drawing, wherein,

Figure 1 shows in perspective the completed tag hereof ready for association with a rug or the like.

Figure 2 is a longitudinal section through the tag on the line 2—2 of Figure 1.

Figure 3 shows the tag hereof after it has been attached to a rug, the flap portion being in naturally drooping position and one of its faces being exposed to view.

Figure 4 is a similar view but showing the flap portion bent upwardly to expose to view its opposite face.

Figure 5 is a miniature perspective view of a pile of rugs carrying the tags hereof.

The tag shown in Figure 1 comprises a substantially rectangular cloth piece or fixable section 10 whose inner face (i. e. the face to be adhesively united to the back of a rug) carries a substantial or thick coating 11 of normally non-adhesive but adhesively activatable substance for ensuring the desired firm union or bond to the back of a rug or the like. The outer face 12 of such section is print-receptive and may be imprinted with the rug-manufacturer's name and/or trademark designated as "XYZ". Such printing may be done on a continuous or lengthy fabric sheet before or after the coating 11 has been applied and the coated sheet then cut up into a number of sections 10; or a continuous or lengthy fabric sheet may first be coated, cut up into the sections 10, and the coated sections printed individually on their uncoated faces 12. The latter procedure is usually practiced when

one establishment does the fabric-coating and sells the coated fabric to the tag manufacturer, who may proceed to cut the coated fabric into the individual sections 10 and suitably imprint 5 such sections or who may cut the fabric into narrow continuous bands or strips, suitably imprint such bands or strips continuously, and finally cut them into the printed and coated individual sections 10.

10 Various substances may be used for the coating 11, including such substances as are adhesively activated by water or by volatile organic liquids. However, it is preferable that the coating 15 be a material or compound, such as rosining compounded rubber, that is thermoplastic or activated by heat, as by the heat of a sadiron preheated to usual clothes-ironing temperatures. If desired, various thermoplastic or thermoadhesive 20 resins or gums, such as the polyvinyl resins or compounds thereof, may serve as the coating 11. The coating materials indicated may be applied 25 to the fabric sheet in the form of liquid solutions containing volatile liquid solvents or in heat-liquified condition and the coating then dried or set so as to enable the finished labels hereof to 30 be stacked for packaging and shipment in normally non-adhesive condition. Because of the substantial or thick coating 11 carried by the fabric section 10, it is stiffened markedly. A 35 substantial or thick coating is necessary, since there is tendency for the coating material to be dissipated to a considerable extent in the back of the rug; and, unless sufficient coating material is provided to allow for such dissipation, the 40 fabric section 11 cannot be united or bonded with the desired tenacity of firmness to the back of the rug.

The flap portion or section of the tag hereof 45 consists of a double-texture fabric or cloth piece 14, which may be of approximately the same shape and dimensions as the fixable section 10. As appears more particularly in Figures 3 and 4, a face 15 of such section may be imprinted with the rug-manufacturer's name and/or trade-mark 50 "XYZ", whereas its other face 16 may be imprinted with such information appurtenant to the rug as its price, dimensions, etc. Double-texture fabric, such as is suitable for the section 14, is available on the market at comparatively low cost and usually comprises individual fabric layers 17 that are comparatively thin and inexpensive and are finished, by reason of particular weave, for printing on only one face. It is, accordingly, the unfinished faces of the two fabric 55 layers 17 that are adhesively united in face-to-face relationship to constitute the double-texture fabric. The adhesive, such as rubber latex or rubber cement, suitable for such purpose exists as a comparatively very thin film 18 between the fabric layers and, accordingly, does not materially stiffen the double-texture fabric, which, as already indicated, is preferably distinctly more flexible than the coated fabric section 10. The 60 comparatively very thin film 18 is necessary to unite the fabric layers 17 into a double-texture fabric whose layers have no tendency whatever to part or separate in use.

The tag sections 14 may be cut from a continuous or lengthy double-texture fabric sheet 65 after the latter has been suitably imprinted on both faces; or the tag manufacturer may cut such sheet, as it is purchased by him on the open market, into continuous bands or strips that may be suitably imprinted on both faces and then 70 cut into the tag sections 14; or, if desired, indi-

vidual tag sections may be cut from such sheet and then be suitably imprinted on both faces. A marginal portion 19 of the tag section 14 may be superposed on a marginal portion of the coated face of the section 10, as shown best in Figures 5 1 and 2, and a suitably preheated sadiron then brought to bear on the superposed portions to activate the thermoadhesive coating 11 appropriately and thus to unite such portions firmly and to provide the finished tag hereof. Of course, 10 when the coating 11 is of a character to require adhesive activation by a volatile liquid, the appropriate liquid is applied thereto before the marginal portion 19 of the section 14 is superposed thereto, preferably under more or less 15 pressure. The two-sectional tags as thus produced may then be packaged and shipped to the rug manufacturer.

In attaching the tag to a rug R, the tag section 10 is placed on the rug so that its coating 11 20 makes contact with the rug back and its flap portion or section 14 projects beyond an edge e of the rug, as depicted best in Figures 3 and 4. Thereupon, a suitably preheated sadiron is passed over the outer face 12 of the section 10 a sufficient 25 number of times to transform the coating 11 to an adhesively-activated state such as to ensure the desired firm union or bond of the section 10 to the rug back. Should the coating 11 require adhesive activation by a volatile liquid, such liquid 30 may be applied thereto in amount to induce the adhesiveness or tackiness desired therein, whereupon the tag may then be attached, preferably under some pressure, to the rug back with its section 14 protruding, as already indicated, 35 beyond the edge e of the rug. It is preferable that the adhesive joint 20 formed between the lapping portions of the two tag sections occur immediately beyond the edge e of the rug. This means that upon sale of the rug, the flap portion 40 14 together with the joint 20 may be cut away, as by scissors, to the very edge e of the rug, thereby leaving permanently attached to the rug the tag section 10, which carries the rug-manufacturer's name and/or trade-mark and which, 45 being adhesively united throughout its inner face to the rug back, does not present any loose or starting edge portions that can be readily grasped, as by children, or that may be accidentally caught and thus facilitate undesired removal or 50 stripping of such section from the rug during its use. In some instances, however, as when the rug is sold on approval, the tag section 14 may be 55 permitted to remain after such sale of the rug, in which case, when the rug is laid or put to use, it may be folded at the edge e under the rug and thus hidden from view.

Because of the relative flexibility of the tag section 14, it droops or flexes freely along a region k immediately beyond or outside the boundary of the adhesive joint 20 formed between the two tag sections. The manner in which the tags of a succession of tagged rugs in a pile may be readily inspected for the information contained 60 on their projecting flap portions or sections 14 is illustrated in Figure 5. The flap portions of each of the tags may easily be bent upwardly, as shown in Figure 4, to enable the ascertainment of the information presented on its face normally 65 hidden from view.

It is to be understood that the inventive principles hereof might be embodied in tags other than the typical one specifically described and illustrated herein and that the appended claims 70 75

should be construed as broadly as the prior art permits.

I claim:

- 5 1. A tag for floor coverings or the like, comprising a substantially rectangular fabric section adapted to be adhesively united to the back face of the floor covering, said section being print-receptive on its outer face and carrying indicia imprinted thereon and being coated on its inner face with normally non-adhesive but adhesively activatable substance in adhesively united relationship with a marginal zone of the floor-covering back, excepting at a marginal portion of said section adjacent to the edge of the floor covering, and a relatively more flexible, double-texture fabric section which is of a width substantially similar to that of said first-named section and a 10 marginal portion of which laps and is adhesively united to a marginal portion of the adhesive-coated face of said first-named fabric section, said second-named fabric section being print-receptive on both its faces and carrying indicia imprinted thereon and said second-named section being adapted to constitute a flap projecting from said floor covering when the coated face of said
- 15
- 20

first-named section is adhesively united to a back marginal zone of said floor covering.

2. The combination with a floor covering or the like, of a substantially rectangular tag comprising a fabric section, said section being print-receptive on its outer face and carrying indicia imprinted thereon and being coated on its inner face with normally non-adhesive but adhesively activatable substance in adhesively united relationship with a marginal zone of the floor-covering back, excepting at a marginal portion of said section adjacent to the edge of the floor covering, and a relatively more flexible, double-texture fabric section a marginal portion of which laps and is adhesively united to the coating on said marginal portion of said first-named fabric section, said second-named fabric section constituting a flap flexing readily at a region thereof immediately beyond the boundary of the adhesive joint between said sections.
